UNITED STATES PATENT OFFICE.

JOHN A. LOCKWOOD, OF FILLMORE, NEW YORK.

ILLUMINATING APPARATUS.

1,421,509.

Specification of Letters Patent.

Patented July 4, 1922.

Application filed January 31, 1921. Serial No. 441,329.

To all whom it may concern:

Be it known that I, JOHN A. LOCKWOOD, a citizen of the United States, residing at Fillmore, in the county of Allegany and 5 State of New York, have invented certain new and useful Improvements in Illuminating Apparatus, of which the following is a specification, reference being had to the accompanying drawings.

10. This invention relates to improvements in illuminating devices and more particularly to means for distributing the light from a single source such as for example, an electric bulb, so that it will be evenly distributed 15 upon a plane surface adjacent the bulb.

A further object of the invention is to provide a novel and improved bulb structure whereby the above result is obtained.

Other objects and advantages of the invention will become apparent in the course 20 of the following description:

In the accompanying drawings, wherein for the purpose of illustration is shown preferred embodiments of my invention,

25. Figure 1 is a front elevation of a sign embodying my invention,

Figure 2 is a rear elevation of the lens employed therein,

Figures 3 and 4 are sections on the lines 30 3-3 and 4-4 of Figure 2 respectively,

Figures 5 to 8 illustrate lenses of uniform density and varying thickness,

Figures 9 and 10 illustrate lenses of uniform thickness and varying density, and

35. Figures 11 to 14 show illuminating bulbs constructed in accordance with my invention.

Referring now more particularly to the drawings, the numeral 10 indicates a source 40 of light, the numeral 11 an objective and the numeral 12 indicates a lens. In the forms shown in Figures 1 to 8, the lens is formed of translucent material resisting but not preventing the passage of light, and the 45 thickness of the lens is varied directly in proportion to the distance of the portions of the lens from the source of light, that is to say, the further these portions lie from the source of light the thinner they are made, so that the light in passing through the lens has its rays variously obstructed, the stronger rays meeting a stronger resistance and this resistance lessening as the distance 50 from the light increases and the strength of the rays decreases, so that upon the opposite side of the lens from the light the projected

light is substantially uniform in strength at all points.

The advantages of a construction of this type when employed with transparent signs 60 and signs upon which flood light is employed, will be readily understood, the light from a single bulb affording a uniform illumination where ordinarily the illumination of the remote portions of a sign with 65 respect to a single bulb would be considerably decreased. As shown in the above described figures, lenses of uniform translucency but of varying thickness may be employed and the construction of the lens may 70 be varied as desired. For example, the lens may be plano-convex, double-convex or cavo-convex.

Instead of employing a lens of uniform translucency and varying the thickness of 75 the lens it will be readily understood that the above result will be accomplished by employing a lens such as shown in Figures 9 and 10, in which the lens is substantially uniform in thickness. The translucency of 80 the lens is, however, varied through the various portions thereof in proportion to the distance of these portions from the source of light so that substantially the same result is obtained thereby. This type of lens may be 85 produced by any of the well known processes. In Figure 1, I have a sign embodying my invention in order that the same may be illuminated with a single globe. As disclosed by the sectional views thereof, a lens construction practically identical with that shown in Figure 6 is employed with the exception of the fact that the back of the lens is provided with ridges 13. In this construction the sign is painted upon the forward or outer 95 face of the lens and the objective of light passing through the lens is accordingly the forward face thereof. It will of course be understood that such is not necessarily the case as the sign might well be painted upon 100 an ordinary sheet of glass and this sheet arranged adjacent the lens.

In many instances it is desirable to have a bulb construction wherein the light emanating therefrom will be evenly distributed 105 upon a given plane surface. Bulbs embodying this construction are shown in Figures 11 and 13, in which the numeral 14 designates the bulb of the globe having formed upon one side thereof a thickened translucent portion 15, the thickness of which varies in such manner that the rays emanat-

ing from the heated wire 16 will be concentrated upon a given plane surface of substantially equal strength. It will of course be understood that, instead of the variable thickness of uniformly translucent material, a uniform thickness of variable translucent material may be employed as shown in Figure 12. In combination with this structure I prefer to provide at the opposite side of the globe from the thickened portion 15 thereof, a reflector 17 which may readily be provided by silvering this portion of the globe. In some instances where a globe is to be employed for illuminating double faced signs, it will be desirable that a thickened portion 15 be provided at each side of the globe as illustrated in Figures 13 and 14. In employing globes of this construction it will of course be understood that the plane surface upon which the light from the globe is acting must be arranged at right angles to a line drawn from the illuminating filament of the globe through the point of greatest density of the thickened portion 15.

From the foregoing it will be obvious that I have provided an illuminating apparatus

which is particularly well adapted for use by reason of the fact that with the employment of a single globe, a uniform distribution of light is afforded, and it will likewise be obvious that the forms hereinbefore set forth are capable of many structural variations not herein shown. I accordingly do not limit myself to the specific forms hereinbefore described except as hereinafter claimed. 35

What I claim is:

1. A lens of uniform thickness and of varying translucency, the translucency increasing uniformly from the center to the edges thereof. 40
2. In combination, a lens of varying translucency and a source of light, the translucency of the lens being such that the amount of light passing through the lens is substantially equal at any two given points in a plane at right angles to a perpendicular passing through the lens and light and at that side of the lens remote from the source of light. 45

In testimony whereof I hereunto affix my 50
signature.

JOHN A. LOCKWOOD.
